UNITED STATES PATENT OFFICE.

WILLIAM D. LUTZ, OF ALLENDALE, NEW JERSEY.

PUMP.

1,141,252.

Specification of Letters Patent.

Patented June 1, 1915.

Application filed July 29, 1913. Serial No. 781,867.

To all whom it may concern:

Be it known that I, WILLIAM D. LUTZ, a citizen of the United States, residing in Allendale, in the county of Essex and State 5 of New Jersey, have invented a new and useful Improvement in Pumps, of which the following is a specification.

My invention relates to improvements in air pumps, in which the piston is actuated 10 by its inertia, and more particularly has for its object to provide a pump of this character for pumping air into the gasolene or oil reservoir or tank of an automobile, wherein the air-pressure in the tank is used to force 15 the gasolene to the carburetor or the oil to the bearings. I attain this object, and others, by the pump hereinafter described and shown in the drawings annexed hereto, as will more fully appear in the description 20 and drawings hereto annexed, in which—

Figure 1 is a view in vertical section of a pump embodying the present invention; Fig. 2 is a top view of the pump, some parts being broken away; Fig. 3 is a view similar 25 to Fig. 1, showing a modified form of a pump; Fig. 4 is a view of an automobile provided with the improved pump.

Similar reference letters refer to similar parts throughout the figures.

30 A casing inclosing the pump, is provided, shown in this instance, as comprising a cylindrical wall, A, with end closures, A' and A². The drawing shows the closure, A', as being integral with the cylindrical wall and the closure A² as being removable therefrom; the closure A' also as having lateral lugs, A³, with perforations, A⁴, and vertical lugs, A⁵, with holes, A⁶, therein, to receive bolts to secure the casing in its applied place 40 and position. There are vents, a, in the casing, Figs. 1 and 2, to allow free passage of the air to and from the inside of the casing. In the casing are two oppositely disposed pump barrels. I have shown the barrels as being preferably integral with the end closures A', A², respectively; but it is obvious that the barrels can be made separate from the closures and be affixed thereto. If the barrels are not made of brass, I prefer to 45

50 line them with brass, the linings, B', being flared outwardly at their inner ends to facilitate the entrance of the pistons in the barrels when assembling the pump. There is an air duct, C, leading from the interior of each barrel B to the exterior of the casing. The ducts, C, have valve seats at the end 55 next to the barrels on which are normally

seated ball valves, D, by springs, E, abutting against the ends of two screw-threaded pipe nipples, F, which are threaded into the 60 casing and are in communication with the ducts C. A pipe, F', connects together the nipples F. Connected to one of the nipples F is a pipe, F², which leads to the pressure tank, F³, shown in Fig. 4. For regulating 65 the pressure in the casing, there is an air duct, I, leading from one of the ducts, C, to the exterior of the casing, through an air duct, I'. There is a ball-valve, J, operatively located between the ducts I and I', 70 normally held to its seat by a spring, L, abutting against a screw threaded pin, M, adjustable to vary the effective pressure of the spring on the ball valve J. By this arrangement, the pressure of the air is regulated. 75 When the air pressure upon the ball valve J overcomes the pressure of the spring L on the valve, and forces the latter from its seat, the air in the duct will escape through the ducts I and I' to the atmosphere. In the 80 pump barrels B are pistons, comprising leather cups, N, held between hollow steel bushings, O and plungers, P, the bushings being secured fast in the end of the plungers. Seated in the bushings, are valves, Q, held 85 in their seats by springs, R, secured in the plungers P, by pins, S, which are let into the plungers through holes T, therein, which latter also serve as air passages. The outer ends of the holes T are closed with screw 90 threaded plugs T'. The pistons are normally held away from the bottoms of the barrels by springs U, shown, in this instance, as coiled around the outside of the barrels and plungers, one end being seated 95 on an extension of the latter, hereinafter described, and the other end on cushions, V, preferably rubber washers placed around the barrels and laid against the inner face of the closures A, A'. In the form of the 100 pump shown, I have provided two barrels, two pistons and two plungers, the latter being integral with each other; but, of course, they may be in separate parts, of two or more pieces and secured together. In the 105 form of the plungers shown, their mass is extended laterally outwardly substantially in the form of flanges surrounding the plungers and barrels, leaving spaces between the walls of the barrels, plungers and flanges 110 for a free movement of the plungers in their barrels. The flanges will take up against the washers, V, in case of violent extreme stroke of the pistons toward the bottom of

the barrels. The extended mass of the plungers is drilled or cored out to constitute air passages, W, communicating with each other, and with the passages T. The drawing only shows in one vertical section the passages T and W, and plug T', but it is to be known that there are like passages and a plug which would be seen were the drawing in vertical section at right angles to the section shown. The springs, U, serve to poise the pistons in the barrels.

In the arrangement of pump shown, a compounding action is secured, as follows, to wit: Assume that the upper piston (as viewed in the drawing) is on its up-stroke, in which operation it will be seen that the air in the casing not in the pump barrels will be displaced and more or less compressed by the upward movement of the plunger mass not in the barrels, and a portion of the air will pass through the passages W, and the valve Q in the lower piston into the lower barrel, the partial vacuum therein created by the upstroke of its piston, accelerating this movement of the air. It will be noted that the air thus confined in the lower barrel will be under a pressure higher than the air in the casing; now, if the pressure of the air in the barrel is higher than the pressure in the tank, the air in the barrel will force the valve D from its seat and pass through the duct C and pipe F' to the tank, or on the other hand, if the pressure of the air in the barrel is lower than the pressure in the tank, the valve D will not be unseated thereby, however, the lower piston upon its return stroke will compound or in other words, further raise the pressure of the air in the barrel to a point sufficient to unseat the valve D, whereupon some of the air will pass from the barrel to the tank. The downward movement of the plunger mass displaces the air and compresses it more or less, and a portion of it will pass through the passages W and valve Q in the upper plunger into the upper barrel. The passages W here meant are those at right angles to those shown and already mentioned.

I have described and shown two barrels and two pistons, but it is obvious that my invention includes the use of more than two barrels or only one barrel and one piston; and, in some if not in the majority of instances, I prefer to use the single barrel and piston.

In Fig. 3 I have shown a modified form of the two barrel type of pump, in which the mass of the plunger is extended laterally to a sliding contact with the inner surface of the wall of the casing. In this example, the air ducts a are omitted, and spring seated intake valves X are seated in the closures A, A'.

The pump in application will be secured

to some part of the automobile, preferably the plungers in vertical position, as shown in the drawings, whereupon unevenness of the road will cause the pistons to stroke in their barrels and pump air through the ducts into the pipe leading to the tank or reservoir, containing gasolene or oil, as the case may be.

Having described and shown my invention, what I desire to claim is:

1. In an air pump, the combination of multi-pump-barrels, a reciprocable casing carrying said barrels, pistons for said barrels operated by inertia, the barrels and pistons positioned opposite each other in substantially the same axial alignment and operable together as a unit.

2. In an air pump, the combination of multi-pump-barrels, a reciprocable casing carrying said barrels, pistons for said barrels, the barrels and pistons set opposite each other in axial alignment, and means consisting of a freely movable body or mass the inertia of which operates the pistons.

3. In a compound acting air pump, the combination of a reciprocable casing, multi-pump barrels, hollow pistons therein, check valves in the pistons, air ducts leading from the barrels to a pressure tank, valves seated between the barrels and tank in the ducts, and a mass affixed to the pistons, freely movable in the casing, the inertia of which mass operates the pistons.

4. In an air pump, the combination of a reciprocable casing, a pump barrel, a hollow piston, therein, a check valve in the piston, an air duct leading from the barrel to a pressure tank, a valve seated between the barrel and tank in the duct, and a mass affixed to the piston, freely movable in the casing, the inertia of which mass operates the piston.

5. In a compound acting air pump, the combination of a casing, multi-pump barrels, hollow pistons therein, check valves in the pistons, air ducts leading from the barrels to a pressure tank, valves seated between the barrels and tank in the ducts, a mass affixed to the pistons movable in the casing, and springs between the top of the said mass and the top of the casing, and between the bottom of the said mass and the bottom of the casing, the first mentioned springs being weaker than those between the bottom of the said mass and the casing, to maintain the said mass in equilibrium.

In testimony whereof I have signed my name to this specification in the presence of two subscribing witnesses.

WILLIAM D. LUTZ.
